DESIGN FOR A FLASHLIGHT CASE

Albert Gelardin, New York, N. Y.

Application July 6, 1936, Serial No. 63,685

Term of patent 14 years

To all whom it may concern:

Be it known that I, Albert Gelardin, a citizen of the United States and residing in the city, county, and State of New York, have invented a new, original, and ornamental Design for a Flashlight Case, of which the following is a specification, reference being had to the accompanying drawing, forming a part thereof.

Figure 1 is a view in side elevation of a flashlight case showing my new design.

Figure 2 is a top plan view of Figure 1.

My design is characterized by a casing as shown, provided with a tapered, truncated globe, said tapered globe having a plurality of outwardly converging panels thereon which terminate at the truncated edge of the globe to give a polygonal paneled effect.

I claim:

The ornamental design for a flashlight case, as shown and described.

ALBERT GELARDIN,
